UNITED STATES PATENT OFFICE.

HOWARD L. WEED, OF DETROIT, MICHIGAN.

ROTARY ENGINE.

1,298,839.

Specification of Letters Patent.

Patented Apr. 1, 1919.

Application filed May 11, 1917. Serial No. 167,993.

To all whom it may concern:

Be it known that I, HOWARD L. WEED, a citizen of the United States, and residing at Detroit, in the county of Wayne and State 5 of Michigan, have invented a new and Improved Rotary Engine, of which the following is a specification.

The present invention has reference to an internal combustion engine of the rotary alternating piston type, and among its important features are the following:—a gearless mechanism for transmitting the driving force from the pistons to the engine shaft; improved means for sealing the joint between the rotors and the cylinders; improvements in the means for sealing the joint between a given piston and the rotor in respect to which it has movement; improvements in the lubricating system; improvements in the cooling system; means for insuring an introduction of fresh gas to the spark plug between explosions; an improved piston construction; and certain other features shown, described and claimed.

25 Certain features of the engine shown and described herein are claimed in my application for United States Letters Patent Serial Number 49,153, filed September 7th, 1915.

30 In the drawings, Figure 1 is a vertical section through a preferred embodiment of the invention, the pistons being substantially at mid-stroke. Fig. 2 is a horizontal section corresponding to Fig. 1. Fig. 3 is a central 35 transverse section, parts being broken away. Fig. 4 is a section on the line 4—4 of Fig. 1. Fig. 5 is an enlarged radial section showing a preferred packing between a rotor and the cylinder. Fig. 6 is an enlarged 40 fragmentary radial section through a piston ring, showing the sealing of the joint between the piston and the adjacent rotor. Figs. 7 and 8 are side and edge views, respectively, of the friction reducing disk between the rotors. Figs. 9 and 10 are side 45 and edge views, respectively, of the oil-pumping fly wheel. Fig. 11 is a longitudinal section of one of the bushings which is interposed between the fly wheel and the 50 roller shafts. Figs. 12 and 13 are detail views showing the means for insuring a delivery of fresh gas to the spark plug. Fig. 14 is a central longitudinal section through one of the rotors. Fig. 15 is a side view 55 looking from the left in Fig. 14. Figs. 16,

17 and 18 are detail views showing the manner of sealing the space between the ends of the piston rings and the adjacent rotors.

In the embodiment of the invention shown, the casing is formed in two sections 1 and 2 60 having bearings 3 and glands 4 for the main engine shaft 5, that may be held from longitudinal movement by the collar 6 and clutch member 8. The casing sections include the substantially annular opposed portions 9 (which form an annular cylinder) bolted together along their marginal flanges 10. As best indicated in Figs. 1, 2 and 4, the sections are each provided with an annular chamber 12 to which cooling water is 65 admitted at the top through a pipe 13 and from which it passes at the bottom as indicated by the arrow (Fig. 1) into a second annular chamber 15 that conforms to the wall of the corresponding half-cylinder; the 70 hot water finally escapes at the top into the pipes 16 which lead to a circulating pump (not shown).

Power transmitting features.—Mounted upon inner bearings 20 and outer bearings 80 21 carried by the shaft 5 are rotors each of which, as best shown in Figs. 14 and 15, preferably comprises an inner barrel 22 and an outer barrel 23 joined by the web 24. The outer barrel has rigid therewith piston 85 blocks 25 spaced 180° apart, and the webs 24 are slotted at 26 transversely of the line joining the centers of the blocks. At points at right angles to said line, the barrels are connected by walls 28—29 which form radial 90 pockets or slots 30.

Interposed between the adjacent ends of the rotors and rigid with the shaft 5 is a counter shaft carrier 34 (Figs. 9 and 10) having its end faces recessed at 35 to receive 95 the corresponding bearing 20 and the end of the corresponding inner barrel 22. For the purpose of receiving the bushings 36, the counter shaft carrier is provided with perforations 38 90° apart; the bushings are 100 pressed into the carrier up to the shoulders 39 and their enlarged ends 40 alternately project in opposite directions.

The bushings 36 have passing therethrough and mounted on bearings 45 therein planetary counter shafts 46 that may be prevented from moving longitudinally by screws 48. At one end each counter shaft has a crank formed with inner and outer cylindrical portions 49 and 50 (preferably 110

of relatively larger and smaller diameters, respectively); and rotatable on these portions are the larger and smaller rollers 51 and 52. The alternate counter shafts are arranged with the cranks at opposite ends, that is, the alternate shafts are reversely arranged. The rollers 51 bear on the outer relatively deep elliptical track or wall 53 and the rollers 52 bear on the relatively shallow elliptical track or wall 54, the tracks, in the present embodiment of the invention, being formed on a track member 55 bolted at 56 to the end wall of the corresponding casing section although they might be integral therewith. The opposite ends of the counter shafts are provided with cranks of greater lengths or eccentricities than those described above, said cranks also being provided with inner and outer cylindrical portions 60 and 61 (preferably of relatively larger and smaller diameters, respectively) carrying larger and smaller rollers 62 and 63. The rollers 62 travel on the walls 28 while the rollers 63 travel on the walls 29, it being understood that these walls are arranged at different distances from the radial plane to which they are parallel to correspond to the difference in the radii of the rollers 62 and 63. By the described relation of rollers 51-52 and tracks 53-54 and the similar relation of rollers 62-63 and tracks 28-29, a close rolling engagement may be maintained at all times without being subjected to the shocks that might arise were a single roller used in each case. When the pistons of the one rotor stand at 90° to those of the other, the slots 26 in each rotor are opposite the slots 30 in the other, and the lengths of the slots 26 is such that 40 the necessary relative angular movements of the rotors in the compression and expansion of the gas is allowed.

The power from the forward impulse of a given piston is transmitted through the 45 wall of its slot 30 to the crank 60-61; and at the same time the re-action from the following piston is transmitted through the wall of its slot 30 to the corresponding crank 60-61. The tendency is therefore to 50 thrust the forward crank 60-61 forwardly and the rearward crank 60-61 rearwardly. But (Fig. 2) the leverage of the forward (left hand, in the position shown) rotor about the corresponding crank 60-61 is 55 greater than that of the rearward (right hand) rotor about the crank 60-61 upon which it acts the maximum difference in the lever arms at the middle of the stroke—the position shown in Figs. 1 and 2—being 60 twice the length of the crank arm. Consequently the net tendency, provided the counter shafts are not capable of rotating freely, is to turn the counter shaft carrier and the main shaft forwardly. The rotation 65 of the counter shafts is controlled by

the travel of the rollers 51-52 in the elliptical grooves formed by the walls 53-54, which cause the countershafts to each make two complete revolutions for each revolution of the main shaft but in the opposite direction; and the rotation of the countershafts, acting through the cranks 60-61 imposes upon the moving rotors a relative angular speed of such nature that the successive pistons are alternately brought near together and farther apart in the cylinder. In other words, although both rotors are always moving forwardly, the speed of a given rotor rises from a minimum to a maximum and then decreases to a minimum during the time that the speed of the other rotor decreases from a maximum to a minimum and thereafter rises again to a maximum. 75

The intake for the fresh gas is indicated at 70 (Fig. 3), the main exhaust passage at 71, and a scavenging passage at 73—the spark plugs 74 (Fig. 2) are substantially diametrically opposite. The movement of the rotors is clockwise looking from the right in Figs. 1 and 2. Therefore in Fig. 3 80 the space 74' is filled with fresh uncomplicated gas, the space 75 with gas that has just been compressed and ignited, the space 76, with fully expanded burned gases which are escaping through the passage 71, while 85 such residual burned gases (from the previous charge) as may have remained in the space 78 are being sucked out through the passage 73 by the current from the passage 71 into the main exhaust pipe 79. The repetition of the cycle between each two successive pistons will be readily understood—there are, of course, four explosions for each turn of the engine shaft. 90

Joint sealing features.—The preferred 105 manner of sealing the joints between the rotors and the cylinder wall is best indicated in Fig. 5. Each cylinder wall or casing section is shaped to form an annular pocket (one wall 81 of which flares outwardly) opening toward the adjacent rotor, and received in the pockets are packing ring carriers each of which includes a base 82, an inner flange 83, an outer flange 84 and an intermediate flange 85. Between the 110 flanges 83 and 85 is received a resilient packing ring 88 one end of which is grooved for a short distance to receive a tongue 90 formed on the other end. The space between the flanges 84 and 85 is preferably left open. 115 The resiliency of the ring 88 tends to hold it in close engagement with the wall 81. It is evident that the resiliency of the ring also tends to force the ring carrier over against the face of the adjoining rotor—an action 120 which is materially increased by the pressure of any gas that may leak past the ring. Preferably, the inner face of the base is 125 grooved circumferentially at 92 to afford chambers for collecting oil and thereby pre- 130

venting leakage of gas around the ring carrier.

Piston construction.—The piston blocks 25 (Figs. 3, 6, 14 and 15) are recessed in their 5 front faces to receive the hubs 100 of the piston heads 101 which are held in said recesses by keys 102 (Fig. 3). The piston heads therefore present flat surfaces upon which the pressure of the gases is applied, 10 thereby avoiding the accumulation of carbon. The piston blocks are grooved at 103 in alignment with the opening into the scavenging passage 73, and the inner faces of 15 the heads may be provided with annular grooves 104 into which fins 105 may project to form increased cooling surfaces. The blocks may also be grooved at 106 on opposite sides in communication with the grooves 104 and 103 and in alignment with the holes 20 108 (Figs. 2 and 3) in the cylinder. Consequently as soon as the grooves 106 come 25 into registration with the holes 108, the exhaust current of gases in the pipe 71, by virtue of the passage 73, draws fresh air in through the piston and tends to cool the latter.

Piston sealing. (Figs. 1, 3, 6, 16, 17 and 18.)—Each of the piston heads has a ring 120 the ends of which are spaced apart some- 30 what, and bear loosely upon the inclined faces 121 and 122 of the sealing members 123 and 124 which correspond in width to the slots for the piston rings. These members also have faces 125 and 126 that bear 35 upon the outer edges of the rotors, and they are further provided with inclined surfaces arranged in a common plane, as indicated at 128, whereby when the members 123 are forced toward the members 124 they are 40 spread apart longitudinally of the engine and held in sealing engagement with the cylinder walls. The piston blocks have longitudinal grooves in which are single resilient bars 126, whereby both members 123 45 for a given piston are constantly pressed against the members 124 on the inclined bearing surfaces 128 and whereby the faces 125 and 126 are held in close contact with the outer edges of the rotors and the intervening member 140.

Spark plug features. (Figs. 2, 3, 12 and 13.)—The spark plugs are screwed into bosses 130 to spark in the chambers 131 that communicate through passages 132 with 50 pockets 133 closed by plugs 134. The entrance from the cylinder to the chambers 131 is through the small openings 135 and the larger opening 136, the latter (Fig. 3) being forwardly of the former. As the compressed charge of fresh gas is swept past the openings 135 and 136 the impure gases which may then surround the electrodes are forced back into the pockets 133 thus bringing the spark into contact with the pure 60 combustible mixture. The high pressure 65

then resulting in the pocket and firing chamber is shortly afterward allowed to gradually escape into the space behind the leading piston ring in the following piston-block, first through the holes 135 and very 70 shortly afterward also through the larger opening 136. The tendency of the direct pressure to collapse the ring is thus reduced.

Friction reduction between rotors.—For the purpose of decreasing friction and providing an element that may be replaced when worn, a disk or ring 140 is loosely mounted on the periphery of the counter shaft carrier and interposed between the rotors. The actual motion of the ring is thus 80 compounded from the movements of the rotors.

Lubricant introduced into the casing is thrown outwardly into the space between the outer barrel of a given rotor and the casing and works out through radial grooves 141 into circumferential grooves 141' (Fig. 6) to the passages 142 and circumferential grooves 142', all of which provide cooling area for the packing devices, rotors and the 90 ring 140. Radial grooves 143 lead inwardly from the circumferential grooves 142' to the spaces between the base of the ring 140 and the inner faces of the outer barrels which run close to the outer surface of the counter-shaft carrier. The last mentioned member (Figs. 9 and 10) has passages 145 (the peripheral openings 146 being wider than the base of the ring 140) that lead backwardly (with reference to the direction of rotation) and inwardly, and then divide and spread outwardly finally intersecting the end faces in the openings 148. As the counter shaft carrier rotates, oil is caught in the openings 146 and delivered through the 100 openings 148 thus creating a sufficient suction to insure a continuous flow, said suction also producing a better and closer sealing engagement of the rotors with the ring 140 and the packing ring carrier flanges 83. It is 110 preferred to groove the counter shaft carrier circumferentially at 150 (Fig. 10) to form pockets which tend to prevent oil from entering between the rotors and establishing a circulation opposed to that just described. 115 The ring 140 is shown provided with perforations 151 (Figs. 2 and 7) which maintain communication between the chambers on opposite sides thereof at all times.

It is evident that the details of construction may be changed within wide limits without departing from the spirit of the invention. I do not, therefore, wish to be limited except as indicated by the subjoined 120 claims.

I claim:

1. A rotary engine comprising a casing, a main shaft mounted therein, said casing including an annular cylinder, a pair of rotors loose on the shaft, each of the rotors 130

- including a pair of pistons arranged to travel in the cylinder, the pistons of the two pairs alternating, means for transmitting force from the rotors to the main shaft, 5 said last named means including countershafts mounted to rotate about axes parallel to but removed from the axis of the main shaft, the rotors being slotted to allow angular movement in respect to the counter-
 10 shafts, said countershafts passing through the slots, and means associated with the countershafts whereby the pistons of one rotor are so constrained as to alternately approach and recede from the pistons of the other, and whereby a pressure of fluid between the pistons may cause the main shaft to rotate.
2. A rotary engine comprising a casing including an annular cylinder, a main shaft 20 mounted in the casing, a countershaft carrier rigid therewith, countershafts mounted in the carrier, the axes of said shafts being parallel to the axis of the main shaft, the countershafts having at their ends cranks 25 of different lengths and being reversely arranged, rotors rotatable about the axis of said main shaft, the rotors being slotted to allow relative angular movement in respect to the countershafts, each rotor including a pair of pistons, the pistons of the two pairs alternating in the cylinder, said rotors also being slotted substantially radially to receive one of the sets of cranks, and elliptical tracks carried by the casing, the other 30 set of cranks coöperating with the tracks, whereby the pistons are constrained to alternately approach and recede from each other, and whereby a pressure of fluid between the pistons may cause the main shaft 35 to rotate.
3. A rotary engine comprising a casing including an annular cylinder, a main shaft mounted in the casing, a countershaft carrier rigid therewith, countershafts mounted in the carrier, the axes of said shafts being parallel to the axis of the main shaft and being spaced from each other substantially 90° about said axis, the countershafts having cranks of different lengths and being 40 reversely arranged, rotors rotatable about the axis of said main shaft, the rotors being slotted to allow relative angular movement in respect to the countershaft, each rotor including a piston, said rotors also being slotted substantially radially to receive a corresponding crank of a given length, and elliptical tracks carried by the casing, the other cranks coöperating with the tracks, whereby the pistons are constrained to alter- 45 nately approach and recede from each other and whereby a pressure of fluid between the pistons may cause the main shaft to rotate.
4. A rotary engine comprising a casing, 50 a main shaft mounted therein, said casing

including an annular cylinder, a pair of rotors angularly movable about said main shaft, each of the rotors including a pair of pistons arranged to travel in the cylinder, the pistons of the two pairs alternating; a 70 countershaft carrier between the rotors and rigid with the main shaft, countershafts mounted in said carrier, the axes of the countershafts being parallel to the axis of the main shaft, the casing, countershafts, 75 rotors and carrier being so constructed and arranged that a movement of one of the rotors relatively to the other causes the main shaft to turn.

5. A rotary engine comprising a casing, 80 a main shaft mounted therein, said casing including an annular cylinder, a pair of rotors angularly movable about said main shaft, each of the rotors including a pair of pistons arranged to travel in the cylinder, 85 the pistons of the two pairs alternating, a countershaft carrier between the rotors and rigid with the main shaft, countershafts mounted in said carrier, the axes of the countershafts being parallel to the axis of the 90 main shaft, the casing, countershafts, rotors and carrier being so constructed and arranged that a movement of one of the rotors relatively to the other causes the main shaft to turn, and a ring loosely mounted on the 95 shaft carrier and interposed between the rotors adjacent the pistons, whereby a direct wearing action of the rotors on each other is avoided.

6. A rotary engine comprising a casing, 100 a main shaft mounted therein, said casing including an annular cylinder, a pair of rotors angularly movable about said main shaft, each of the rotors including a pair of pistons arranged to travel in the cylinder, 105 the pistons of the two pairs alternating, a countershaft carrier between the rotors and rigid with the main shaft, countershafts mounted in said carrier, the axes of the countershafts being parallel to the axis of the 110 main shaft, and means acting on the countershafts whereby an angular movement of the rotors relatively to one another causes the countershafts to travel bodily about the axis of the main shaft.

7. A rotary engine comprising a casing, a main shaft mounted therein, said casing including an annular cylinder, a pair of rotors angularly movable about said main shaft, each of the rotors including a pair of pistons arranged to travel in the cylinder, the pistons of the two pairs alternating, a countershaft carrier rigid with the main shaft, countershafts rotatably mounted in said carrier, the axes of the countershafts 120 being parallel to the axis of the main shaft, the rotors being slotted and the countershafts passing through the slots whereby the rotors are allowed angular movement in respect to the countershaft carrier, and 125 130

means associated with the countershafts whereby an angular movement of the rotors relatively to one another causes the countershafts to travel bodily about the axis of 5 the main shaft to turn said main shaft.

8. A rotary engine comprising a casing, a main shaft rotatable therein, rotors co-axial with said shaft, whereby lubricant in the casing is thrown outwardly as the rotors 10 rotate about the axis of the main shaft, an element secured to the shaft and rotatable therewith, said element having a passage leading inwardly and backwardly from its periphery into which lubricant is scooped 15 and drawn inwardly toward the axis of the shaft to insure continuous circulation.

9. A rotary engine comprising a casing, a main shaft rotatable therein, rotors co-axial with said shaft, whereby lubricant in 20 the casing is thrown outwardly between the rotors and the casing as the rotors rotate about the axis of the main shaft, and means for thereafter drawing the lubricant inwardly toward the main shaft whereby a 25 continuous circulation is established.

10. A rotary engine comprising a casing including an annular cylinder, a main shaft rotatable in the casing, alined rotors co-axial with said shaft and having pistons 30 thereon located in the cylinder, the rotors having angular movement in respect to each other and being rotatable about the axis of the main shaft whereby lubricant in the casing is thrown outwardly as the rotors 35 revolve, and means interposed between the rotors whereby the lubricant is thereafter drawn back toward the axis of the main shaft to insure continuous circulation.

11. A rotary engine comprising a casing 40 including an annular cylinder, a main shaft rotatable in the casing, alined rotors co-axial with said shaft and having pistons thereon located in the cylinder, sealing means between the faces of the rotors and 45 the corresponding faces of the cylinder, the rotors being rotatable about the axis of the main shaft whereby lubricant in the casing is thrown outwardly along the sealing means as the rotors revolve, and means for there- 50 after drawing the lubricant inwardly toward the axis of the main shaft to insure continuous circulation.

12. A rotary engine comprising a casing including an annular cylinder, a main shaft 55 rotatable in the casing, alined rotors co-axial with said shaft and having pistons thereon located in the cylinder, sealing means between the faces of the rotors and the corresponding faces of the cylinder, the 60 rotors being rotatable about the axis of the main shaft whereby lubricant in the casing is thrown outwardly along the sealing means as the rotors revolve, and means for creating a suction between the adjacent ends 65 of the rotors whereby the lubricant is there-

after drawn in toward the axis of the main shaft and whereby the rotors are caused to tend to approach each other.

13. A rotary engine comprising a casing including an annular cylinder, a main shaft 70 rotatable in the casing, alined rotors co-axial with said shaft and having pistons thereon located in the cylinder, sealing means between the faces of the rotors and the corresponding faces of the cylinder, the 75 rotors being rotatable about the axis of the main shaft whereby lubricant in the casing is thrown outwardly along the sealing means as the rotors revolve, a ring interposed between the rotors and rotatable about 80 the axis of the main shaft, and means for creating suction about said ring whereby the lubricant is drawn in toward the axis of the main shaft.

14. A rotary internal combustion engine 85 comprising a casing including an annular cylinder, alined rotors having peripheral flanges projecting to the inner zone of the cylinder, means for sealing the joints between the flanges and the cylinder, and 90 means for drawing lubricant which may be thrown out between the rotors and the sealing means back toward the axis of the rotors through the space between the rotors, whereby the flanges are cooled by a continuous 95 circulation of lubricant.

15. A rotary engine comprising a casing, a main shaft rotatable therein, rotors co-axial with the shaft and arranged to move angularly in reference to each other about 100 said shaft and to rotate about the axis thereof, a countershaft carrier rigid with the shaft, said carrier being interposed between the rotors, means associated with the countershaft carrier for causing a relative movement of the rotors to be transmitted to the main shaft, and a ring loosely mounted on the countershaft carrier and interposed between the rotors, whereby a direct wearing action of the rotors on each other is avoided. 110

16. Means for sealing the joint between the casing of a rotary engine and an annular surface of a rotor, said means including an annular ring carrier seated in a groove in the casing and bearing on the rotor, said 115 groove having a surface inclined to the axis of the rotor, the ring carrier having a sealing ring therein resiliently engaging the inclined surface to force the ring carrier against the rotor, the ring carrier also having a groove therein which with a portion of the inclined surface forms a pocket for gases that may escape past the sealing ring, whereby the pressure of the escaped gases is utilized to force the ring carrier against 120 the rotor.

17. Means for sealing the joint between the casing of a rotary engine and an annular surface of a rotor, said means including 125 an annular element seated in an annular 130

groove in the casing and arranged to bear against the rotor, the groove having an inner wall and an outer wall, and the annular element having an annular groove there-
 5 in opening to a wall of the groove in the casing other than the outer wall, wherein oil may collect to prevent the escape of gases past the element.

18. Means for sealing the joint between
 10 the casing of a rotary engine and an annular surface of a rotor, said means including an annular element seated in an annular groove in the casing and arranged to bear against the rotor, the groove having an inner
 15 wall and an outer wall, and the annular element having a groove therein opening to the inner wall of the groove in the casing, wherein oil may collect to prevent the escape of gases past the element.

20 19. A rotary engine comprising a casing including an annular cylinder, a pair of aligned rotors each having a piston received in the cylinder, means for sealing the joint between one of the rotors and the piston of
 25 the other rotor comprising a pair of elements constructed and arranged to be spread apart longitudinally of the common axis of the rotors by a pressure substantially radially of said rotors and means for exerting pressure
 30 on one of the members substantially radially of said rotors to cause a sealing action.

20. A rotary engine comprising a casing including an annular cylinder, a pair of rotors each having a piston received in the cylinder, fractional piston rings for the pistons, and means for sealing the joint between the piston rings of one of the rotors and the other rotor, comprising a pair of elements constructed and arranged to be spread apart
 35 longitudinally of the common axis of the rotors and against the ends of the piston ring by a pressure substantially radially of said rotors, and resilient means for exerting pressure on one of the members substantially

radially of said rotors to cause a sealing action.

45

21. A rotary engine comprising a casing including an annular cylinder, a rotor having a piston block arranged to travel in the cylinder, piston heads on opposite sides of the block, and means located entirely on 50 the sides of the heads adjacent the block for securing said heads to the block.

22. A rotary engine comprising a casing including an annular cylinder, a rotor having a piston block arranged to travel in the 55 cylinder, piston heads on opposite sides of the block, the blocks having sockets and the heads having projections received in the sockets, and keys passing transversely through the projections for retaining the 60 heads on the blocks.

23. An internal combustion engine comprising a cylinder, a spark plug chamber communicating therewith, a spark plug in the chamber, and a closed pocket communicating with the spark plug chamber into which residual gases from a previously 65 burned charge are forced by the compression of fresh gas in the cylinder, whereby said fresh gases are allowed to come into intimate 70 contact with the spark plug.

24. A rotary internal combustion engine including an annular cylinder and a spark plug chamber opening into said cylinder, a spark plug in the chamber, pistons traveling 75 in the same direction in the cylinder and arranged to approach and recede from each other in their movement, a closed chamber into which burned gases from a previous charge are swept by the compression of fresh 80 gases in the cylinder as the pistons approach each other, and means for gradually relieving the pressure in the spark plug chamber through the space to the rear of the front face of the rear piston.

HOWARD L. WEED.
